US00D909007S

(12) **United States Design Patent** (10) Patent No.: **US D909,007 S**
(45) Date of Patent: **** Feb. 2, 2021**

(54) **THIN BISCUIT SANDWICH**(71) Applicant: **Intercontinental Great Brands LLC**,
East Hanover, NJ (US)(72) Inventors: **Dongxu Wang**, Suzhou (CN); **Yong Shi**, Suzhou (CN); **Weiying Qian**, Suzhou (CN); **Guoqiang Xue**, Suzhou (CN); **Manhu Gu**, Suzhou (CN)(73) Assignee: **Intercontinental Great Brands LLC**,
East Hanover, NJ (US)(***) Term: **14 Years**(21) Appl. No.: **29/522,223**(22) Filed: **Mar. 27, 2015****Related U.S. Application Data**(63) Continuation-in-part of application No. 29/503,952,
filed on Sep. 30, 2014.**Foreign Application Priority Data**

Mar. 30, 2014 (CN) 2014 3 0070448

(51) LOC (13) Cl. **01-01**

(52) U.S. Cl.

CLAIM

The ornamental design for a thin biscuit sandwich, as shown and described.

DESCRIPTION

FIG. 1 is a front elevation view of a first embodiment of a thin biscuit sandwich, the left, right and rear elevation views being identical thereto;

FIG. 2 is a perspective view of the thin biscuit sandwich of FIG. 1;

FIG. 3 is a top plan view of the thin biscuit sandwich of FIG. 1, the bottom plan view being identical thereto;

FIG. 4 is a front elevation view of the thin biscuit sandwich of FIG. 1, but showing an open state;

FIG. 5 is a top plan view of the open state of the thin biscuit sandwich of FIG. 1;

FIG. 6 is a front elevation view of a second embodiment of a thin biscuit sandwich, the left, right and rear elevation views being identical thereto;

FIG. 7 is a perspective view of the thin biscuit sandwich of FIG. 6;

FIG. 8 is a top plan view of the thin biscuit sandwich of FIG. 6, the bottom plan view being identical thereto;

FIG. 9 is a front elevation view of the thin biscuit sandwich of FIG. 6, but showing an open state; and,

FIG. 10 is a top elevation view of the open state of the thin biscuit sandwich of FIG. 6.
